STRAP TENSIONING TOOL

Michael O. Derrickson, Norwood, Pa., assignor to American Viscose Corporation, Philadelphia, Pa., a corporation of Delaware

Filed Nov. 15, 1961, Ser. No. 152,590
8 Claims. (Cl. 140—123.6)

This invention relates to the art of applying flexible straps about an article or group of articles and more particularly to an improved strap tensioning tool.

It is an object of the invention to provide a strapping tool having power operated strap tensioning means and so constructed that a single motion on the part of the operator is effective to cut the strap to length and discontinue the application of power to the strap tensioning means.

Another object of the invention is to provide a strap tensioning tool having power means for tensioning a strap about one or more articles and a common operating member for controlling the power means and cutting the strap to length.

Toward the attainment of the foregoing objects the invention provides a strap tensioning tool having novel structural features, as will now be explained by reference to the accompanying drawing showing a preferred embodiment, wherein:

FIG. 1 is a side elevational view of the tool showing portions of the internal mechanism in dotted lines;

FIG. 2 is an end elevational view of the tool;

FIG. 3 is a fragmentary plan view of the front end of the tool, certain internal parts being shown in dotted lines;

FIG. 4 is a fragmentary side elevational view of the front end of the tool;

FIG. 5 is an elevational view of the lower portion of the tool looking from the right-hand side of FIG. 1;

FIG. 6 is an exploded view showing a valve constituting one of the elements of the invention; and

FIG. 7 is a sectional view taken along the line VII—VII of FIG. 1.

The tool comprises a housing consisting of two castings 10 and 11. Casting 10 forms the forward end of the tool and supports the strap engaging elements and casting 11 houses most of the driving mechanism and includes a more or less cylindrical handle portion 12. A bore 13 extends longitudinally of the handle portion 12 of casting 11 and at its forward end communicates with a conduit 14 leading to a valve, generally indicated at 15. A hose 16 is connected to the end of handle portion 12 and discharges into bore 13. A conduit 17 communicates at one end with valve 15 and at the other joins an end of a bore 18 extending rearwardly through the handle portion 12 parallel to bore 13. A plug 19 closes the outer end of bore 18 and a short conduit 20 connects bore 18 to a chamber 21 within casting 11. A fluid motor 22, preferably an air motor, is mounted within chamber 21 and the drive shaft of said motor is provided with a pinion 23 situated within a hollowed-out portion of casting 10. Pinion 23 meshes with a gear 24 secured to a shaft 25 mounted in suitable bearings within castings 10 and 11. Shaft 25 extends through the front face of casting 10 and a slotted capstan or strap-winding drum 26 is secured to said shaft. When valve 15 is open, compressed air from line 16 passes to the air motor 22 to cause said motor to rotate capstan 26. Since the particular construction of air motor 22 is not of the essence of the present invention, no details thereof are shown. However, for a reason later to be explained, it is necessary that motor 22 be of the type which will impart a constant torque to capstan 26 so long as it is supplied with air at a constant pressure. Many such motors are available on the market.

2

The tool of the present invention is adapted to be used in the same manner as the tool shown in U.S. Patent No. 2,881,636 to Palmleaf and includes a strap guiding element 27 carried by casting 10. Guiding element 27 is provided with a nose or end 28 adapted to bear against a so-called closed seal to which one end of the strap is connected and through which another portion of the strap passes freely. Element 26 is also provided with a guide slot 29 through which the strap passes before being engaged with one of the slots in windlass 26. Upon rotation of the windlass in a counterclockwise direction, as viewed in FIG. 2, the strap is wound thereabout to tighten it about one or more articles around which it has been looped and the seal is then crimped about the overlapping portions of the strap to secure the same together. This mode of operation is explained in the above-mentioned patent to Palmleaf.

So that the strap may be cut to length after it has been sealed about the article, strap guiding element 27 is provided with a cutter 30. Cutter 30 is in the form of a shaft rotatably mounted in element 27 and having a flattened surface aligned with slot 29. When the shaft or cutter 30 is rotated in a clockwise direction, as viewed in FIG. 2, the edge of the flattened surface contacts the strap passing through slot 29 and in cooperation with an edge 31 of said slot is effective to cut the strap between capstan 26 and the seal which is butted against the nose 28 of guide element 27.

An arm 32 is secured to one end of cutter shaft 30 and said arm carries a pin 33 engaged with a slot 34 provided in a tab 35 secured to or formed integrally with a leg 36 of a bale 37. Bale 37 constitutes a cutter operating handle and has another leg 38 extending parallel to leg 36. Legs 36 and 38 are pivotally mounted near their lower ends on pins 39 and 40 respectively, secured to and extending outwardly from casting 11 of the tool housing. A spring 41 operating between arm 32 and a shoulder 42 of strap guiding element 27 urges cutter shaft 30 to the inactive or non-cutting position shown in FIG. 2 and, through pin 33 and slot 34 of tab 35, urges bale 37 toward the forward position shown in full lines in FIG. 1. Movement of the handle 37 to the dotted line position shown in FIG. 1 is effective to operate cutter 30.

Valve 15 comprises a cylindrical member 43 which fits within a cylindrical bore 44 extending in from one side of casting 11, see particularly FIG. 6. Member 43 is provided with a groove 45 engaged with which is a set screw 46 which holds the valve member within bore 44 but permits limited longitudinal movement thereof. Resilient means in the form of a spring 47 is located between valve member 43 and the inner end of bore 44 and urges member 43 toward the left as viewed in FIGS. 5 and 6, this movement being limited by the engagement of set screw 46 within groove 45. The hereinbefore mentioned conduits 14 and 17 communicate with bore 44 and when member 43 is in the position shown in FIG. 5 it blocks conduits 14 and 17 so that compressed air from line 16 cannot reach motor 22. Valve member 43 is provided with a slot 48 and with a finger piece or manually operable means 49 and when said valve member is pushed inward against the action of spring 47, notch 48 becomes aligned with conduits 14 and 17 so that air from line 16 may pass through the valve. When valve 15 is open as shown in FIG. 5 leg 38 of bale handle 37 is held against a cylindrical portion of valve member 43 by the spring 41. When valve member 43 is pushed inward to open the valve a notch 50 of the valve member becomes aligned with the forward edge of leg 38 and spring 41 causes leg 38 to move into the notch to thus hold the valve in open condition. Upon movement of cutter operating handle 37 to the dotted line position

shown in FIG. 1 to cut the strap as aforesaid, leg 38 becomes disengaged from notch 50 and the valve is closed by the spring 47.

In use, the tool is engaged with the strap in the manner shown in the Palmleaf patent and the operator depresses finger piece 49 to open valve 15 and thereby cause the strap engaging element or capstan 26 to be rotated by motor 22 to tighten the strap about one or more articles around which it has been looped. When valve 15 is opened, the notch 50 becomes aligned with leg 38 so that spring 41 is able to move said leg into the notch and thereby hold the valve in open condition. Valve member 43 may be referred to as a motor control member and notch 50 of member 43 and leg 38 of cutter operating handle 37 constitute cooperating means for holding member 43 in a first position, that is, in motor operating position. The air pressure in line 16 may be regulated in any suitable manner and the pressure in said line determines the rotating force or torque applied by motor 22 to capstan 26. When the preselected tension is applied to the strap, as determined by the pressure in line 16, motor 22 will stall and maintain the tension on the strap while the seal is crimped about the strap. Handle 37 is then moved rearwardly to the dotted line position shown in FIG. 1 to cut the strap to length and this same movement is effective to disengage leg 38 from notch 50 and thereby permit spring 47 to move valve member 43 to the position shown in FIG. 5 to cut off the supply of air to the motor.

Having thus described a preferred embodiment of the invention, what is claimed is:

1. A strapping tool comprising a housing, a strap guiding element on said housing, a cutter member associated with said strap guiding element, strap engaging means for pulling a portion of a strap through said guiding element to tighten the same about a package, a motor mounted in said housing for moving said strap engaging means, a control member movable to a first position for causing said motor to operate said strap engaging means and to a second position for preventing said motor from operating said strap engaging means, resilient means normally holding said control member in its said second position, manually operable means for moving said member to its said first position, a cutter operating handle mounted on said housing, means interconnecting said handle and said cutter member whereby movement of said handle to a first position operates said cutter member, means urging said handle to a second position, and cooperating means on said handle and said control member to hold said control member in its said first position when said handle is in its said second position.

2. A strapping tool comprising a housing, a strap guiding element on said housing, a slot extending through said strap guiding element through which a portion of a flexible strap is adapted to be drawn to tighten the same about a package, a cutter member mounted in said strap guiding element for selectively cutting the strap, a windlass for drawing the strap through said slot, a motor mounted in said housing for driving said windlass, a control member movable to a first position for causing said motor to drive said windlass and to a second position for discontinuing the driving of said windlass by said motor, resilient means normally holding said control member in its said second position, manually operable means for moving said member to its said first position, a cutter operating handle mounted on said housing, means interconnecting said handle and said cutter member whereby movement of said handle to a first position operates said cutter member, means urging said handle to a second position, and cooperating means on said handle and said control member to hold said control member in its said first position when said handle is in its said second position.

3. A strapping tool comprising a housing, a strap guiding element on said housing, a slot extending through

4
said strap guiding element through which a portion of a flexible strap is adapted to be drawn to tighten the same about a package, a cutter member for selectively cutting the strap, means for drawing the strap through said slot, 5 said means comprising a fluid operated motor mounted in said housing, a conduit for supplying fluid to said motor, a valve in said conduit, resilient means normally positioning said valve so as to prevent the passage of fluid to said motor, manually operable means for moving said valve to a position to permit the passage of fluid to said motor, a cutter operating handle mounted on said housing, means interconnecting said handle and said cutting member whereby movement of said handle to a first position operates said cutting member to cut the strap, 15 spring means urging said handle to a second position, and cooperating means on said handle and said valve for holding said valve in position to permit the passage of fluid to said motor when said operating handle is in its said second position.

4. A strapping tool comprising a housing, a seal engaging element on said housing, a slot extending through said seal engaging element through which a portion of a flexible strap is adapted to be drawn to tighten the same about a package, a cutter member mounted in said seal engaging element for selectively cutting the strap, strap engaging means for drawing the strap through said slot, a motor mounted in said housing for moving said strap engaging means, a motor control member movable to a first position for activating said motor and to a second position for stopping said motor, resilient means normally holding said motor control member in its said second position, manually operable means for moving said member to its said first position, a cutter operating handle mounted on said housing, means interconnecting said handle and said cutter member whereby movement of said handle to a first position operates said cutter member, means urging said handle to a second position, and cooperating means on said handle and said motor control member to hold said motor control member in its said first position when said handle is in its said second position.

5. A strapping tool comprising a housing, a seal engaging element on said housing adapted to press against a seal with respect to which one end of a strap is fixed and through which another portion of the strap is adapted to be drawn to tighten the strap about a package, a cutter member for selectively cutting the strap, strap engaging means for drawing the strap through the seal, a motor mounted in said housing for moving said strap engaging means, a control member movable to a first position for causing said motor to operate said strap engaging means and to a second position for preventing said motor from operating said strap engaging means, resilient means normally holding said control member in its said second position, manually operable means for moving said member to its said first position, a cutter operating handle mounted on said housing, means interconnecting said handle and said cutter member whereby movement of said handle to a first position operates said cutter member, means urging said handle to a second position, and cooperating means on said handle and said control member to hold said control member in its said first position when said handle is in its said second position.

6. A strapping tool comprising a housing, a seal engaging element on said housing adapted to press against a seal with respect to which one end of a strap is fixed and through which another portion of the strap is adapted to be drawn to tighten the strap about a package, a cutter member mounted in said seal engaging element for selectively cutting the strap, a windlass for drawing the strap through the seal, a motor mounted in said housing for driving said windlass, a motor control member movable to a first position for activating said motor and to a second position for stopping said motor, resilient means normally holding said motor control member in its said second position, manually operable means for mov-

ing said member to its said first position, a cutter operating handle mounted on said housing, means interconnecting said handle and said cutter member whereby movement of said handle to a first position operates said cutter member, means urging said handle to a second position, and cooperating means on said handle and said motor control member to hold said motor control member in its said first position when said handle is in its said second position.

7. A strapping tool comprising a housing, a seal engaging element on said housing, a slot extending through said seal engaging element through which a portion of a flexible strap is adapted to be drawn to tighten the same about a package, a cutter member mounted in said seal engaging element for selectively cutting the strap, strap engaging means for drawing the strap through said slot, a fluid operated motor mounted in said housing for moving said strap engaging means, a conduit for supplying fluid to said motor, a valve in said conduit, resilient means normally positioning said valve so as to prevent the passage of fluid to said motor, manually operable means for moving said valve to a position to permit the passage of fluid to said motor, a cutter operating handle mounted on said housing, means interconnecting said handle and said cutting member whereby movement of said handle to a first position operates said cutting member to cut the strap, spring means urging said handle to a second position, and cooperating means on said handle and said valve for holding said valve in position to permit the passage of fluid to said motor when said operating handle 30 is in its said second position.

8. A strapping tool comprising a housing, a strap guiding element on said housing, a slot extending through said strap guiding element through which a portion of a flexible strap is adapted to be drawn to tighten the same about a package, a cutter member for selectively cutting the strap, a windlass for drawing the strap through said slot, a fluid operated motor mounted in said housing for driving said windlass, a conduit in said housing for supplying fluid to said motor, a valve in said conduit, resilient means normally positioning said valve so as to prevent the passage of fluid to said motor, manually operable means for moving said valve to a position to permit the passage of fluid to said motor, a cutter operating handle mounted on said housing, means interconnecting said handle and said cutting member whereby movement of said handle to a first position operates said cutting member to cut the strap, spring means urging said handle to a second position, and cooperating means on said handle and said valve for holding said valve in position to permit the passage of fluid to said motor when said operating handle is in its said second position.
